United States Patent Office.

W. S. HUDSON, OF PATERSON, NEW JERSEY.

Letters Patent No. 66,964, dated July 23, 1867.

IMPROVEMENT IN PISTON-PACKING.

The Schedule referred to in these Letters Patent and making part of the same.

TO ALL WHOM IT MAY CONCERN:

Be it known that I, WILLIAM S. HUDSON, of Paterson, in the county of Passaic, and State of New Jersey, have invented certain new and useful improvements in Packing Pistons; and I do hereby declare that the following is a full and exact description thereof.

My invention will serve for packing for pistons, for pumps, and for various other uses, but is intended more especially for the pistons of steam engines. I employ two kinds of packing-rings in combination. One kind is set out and adjusted by screws or analogous mechanism; the other is set out or adjusted by the action of the steam.

I will first describe what I consider the best means of carrying out my invention, and will afterwards designate the points which I believe to be new. The accompanying drawings form a part of this specification.

Figure 1 is a face view of my piston, a part of the follower being removed to show the interior parts.

Figure 2 is an edge view partly in section.

Figure 3 is a section of a part, showing a modification in the construction.

Figures 4, 5, and 6 represent another modification.

Similar letters of reference indicate corresponding parts in all the figures.

Tints are employed merely to aid in distinguishing parts, and do not necessarily indicate material. The material of the parts may be cast iron and steel.

Referring to figs. 1 to 3, A is the main body of the piston. A¹ is the follower, a part bolted on the part A to make the framing or rigid portion of the piston complete. B¹ B² are steam-packed rings; having the channels b¹ b² of less width than the said rings extending around under them, which channels are connected by small holes a¹ a², the channels under the ring B¹ communicating with one face of the piston, and the channels under the ring B² communicating with the other face. C is a stout ring which is tightly clasped between the parts A and A¹ and B¹ B² of the piston, and which is adjusted by means of screws D and quite rigid springs, in fact the almost inflexible parts E, which bear upon the interior face of the ring C, as represented. These parts are adjusted readily by nuts and jam-nuts, as represented. On taking off the follower A¹, access is obtained to these nuts, so that the packing may be set out to any required extent with great nicety. The ring C is represented as divided only at one point; but it may have three or any other number of such divisions if preferred. The joint is carefully defended against leakage of the steam at that point. The splicing piece is represented by G. The main body of this piece extends along inside of the ring C, and is exactly equal in width to the said ring. Two thin broad lips extend radially outward from the main body G, as indicated by G¹ G², and the ring C is recessed to receive these and to fit as accurately thereto as possible, a portion of the recess for each being made each side of the joint. In other words, the lips G¹ G² are let into the two faces of the ring C, so as to break joints therewith, and cover and protect the opening. The exterior edges of the lips G¹ G² are just flush with the exterior of the surface of the packing-ring C. The inner face of the splicing-piece G is extended inward at each end, as indicated by g g. These hooks or projections embrace the ends of the corresponding spring E, so that the splicing-piece cannot move except to a very limited extent. It follows that the packing-ring cannot become displaced by turning around in the piston, even if it were not clamped firmly between the parts A and A¹.

Operation.

The diameters of the rigid parts A and A¹ are necessarily a little less than the interior of the cylinder in which they are to work. The main ring C is adjusted readily by means of the nuts on the screws D until the packing-ring C just fills the interior of the cylinder. It is intended that this ring shall always traverse very nearly steam-tight, but not with such a pressure against the interior of the cylinder as could be fully relied on to prevent the passage of steam. Thus conditioned the ring C causes but a very slight friction. I have experimented with the construction on locomotives, and prefer to fit the ring C so that while it touches the interior of the cylinder all around, the movement of the piston shall be opposed so slightly by friction that it can be drawn forward and pushed back easily by the hands. After this ring C has been thus nicely adjusted, the main body touching the cylinder all around and the lips G¹ and G² covering the joint, and defending it against allowing

a passage of the steam, the parts A A¹ are tightly drawn together so as to seize the two faces of the ring C and of the splicing-piece, and to hold it very firmly and steam-tight, so that no appreciable amount of steam can traverse across under this adjustable packing-ring. Thus conditioned the piston is set at work. As the steam is successively received, first on one side of the piston and then on the other, to impel it backwards and forwards, the steam-packed rings B¹ B² are alternately expanded by the pressure of the steam beneath them. For example, the steam going on that side at full pressure flows along through the holes a¹, and filling the groove b¹ and the small additional space within the ring B¹ swells this ring outward so that it fits tightly against the interior of the cylinder. It thus covers and defends the very slight joint or leak which might otherwise exist between the exterior of the adjustable ring C and the interior of the piston, and defends the piston against leakage, except at the very narrow space where the steam-packed ring B¹ is divided. Precautions may be taken to defend this joint by a tongue or otherwise, but I do not deem it necessary. The packing-ring C is so tight that the very small joint in the steam-packed ring B may be left undefended. The moment that the steam is exhausted from this side of the piston the pressure on the interior of the steam-packed ring B¹ is reduced and the ring shrinks or diminishes its diameter. This movement need not take place, as will be well understood by steam engineers, except to a very slight extent, in order to practically reduce the friction between this and the interior of the cylinder to an inappreciable amount. As the steam is received and discharged on the other side of the piston, the same effect occurs with the other steam-packed ring B². Thus, as the piston reciprocates in the cylinder under the action of the steam pressure, first on one side and then on the other, the piston travels steam-tight and with very little resistance, the stout adjustable ring, with its splicing-piece filling the cylinder, with a gentle pressure against the interior, and the steam-packed rings B¹ B² alternately swelling and contracting to form an additional security against the leakage of steam.

It will be observed that the adjustable ring C, with its splicing-piece, being set out and held firmly by means of the very great rigidity of the springs E, always holds the piston up in the centre of the cylinder. The steam-packed rings B¹ B² do not have to lift the piston at each movement to get into a central position in the cylinder. It is always held there by the adjustable ring.

In order to avoid the possibility that the stiff springs E may become displaced so as not to perform their functions perfectly, I produce a small protection or support extending radially outward from the end of each, as indicated by e, and make a corresponding recess or groove extending around on the interior of the adjustable ring C, as indicated by e. Babbit metal or other soft metal may be used, as indicated by I, if desired.

The packing-ring C is represented in the above-described figures as a single ring. It may be made in many more complex forms if desired. It may in fact be made in most, if not all, of the indefinite variety of modifications in which adjustable packings have been heretofore made, but I deem it important that it be not mounted in any manner which is very sensibly elastic. In other words, I wish it to be very rigid, so that it shall not accommodate itself to any inequalities or tapering in the form or any increase in the size of the cylinder due to wear or other causes. It shall be sure to hold the centre of the piston very truthfully in or extremely near to the axis of the cylinder.

Figure 3 represents a section of a modification of the packing which may be used with success. In this figure H represents an interior ring, with its splicing piece adapted to apply within the main ring C. Figures 4, 5, and 6 represent still further modifications, wherein the inner ring H is divided into parts and the splicing-piece is made to apply in a space along the central joint.

Having now fully described my invention, what I claim as new in the packing of pistons, and desire to secure by Letters Patent, is as follows:

1. I claim the combination of the adjustable packing-ring C with one or more steam-packed rings B¹ B², so as to operate together substantially as and for the purpose herein specified.
2. I claim the parts A¹ A² of the piston adapted for clamping the adjustable ring C, as specified, in combination with steam-packed rings B¹ B² or their equivalents, as and for the purpose herein specified.
3. I claim, in combination with packing-rings arranged to operate substantially as herein specified, the projections g and piece E, adapted for holding the splicing-piece G G¹ G², and consequently the whole adjustable ring C against turning around in the piston, substantially as and for the purpose herein set forth.

W. S. HUDSON.
